UNITED STATES PATENT OFFICE.

FRANK W. SEVERIN, OF CHICAGO, ILLINOIS, ASSIGNOR TO VENN-SEVERIN MACHINE CO., OF CHICAGO, ILLINOIS, A CORPORATION OF ILLINOIS.

GOVERNOR MECHANISM.

1,074,652.

Specification of Letters Patent.

Patented Oct. 7, 1913.

Application filed March 2, 1911. Serial No. 611,930.

To all whom it may concern:

Be it known that I, FRANK W. SEVERIN, a resident of Chicago, in the county of Cook and State of Illinois, have invented certain 5 new and useful Improvements in Governor Mechanism, of which the following is a full, clear, and exact description.

The invention relates to governor-mechanism for internal combustion engines, 10 whereby liquid-fuel supplied to the engine cylinders will be regulated in accordance with the speed of the engine. In governors of this type, it is desirable to avoid, so far as possible, wear and friction of the governor-parts and connections between the 15 governor and the pump, so that variation of the fuel-supply will not occur as a result of wear of the connections and frictionally engaging parts.

20 One object of the invention is to provide governor-mechanism of simple construction, whereby the liquid-fuel supply will be regulated according to the speed of the engine, the parts being organized to reduce wear 25 and friction, so far as possible.

Another object of the invention is to provide improved means for adjusting the operation of the pump or pumps by the governor-operated mechanism, so that the 30 amount of fuel supplied may be regulated to a nicety in accordance with the operation of the governor.

The invention consists in the several novel features hereinafter set forth and more particularly defined by claims at the conclusion hereof.

40 In the drawings: Figure 1 is a front elevation of an internal-combustion engine embodying the invention. Fig. 2 is a side elevation, the fly-wheel and the governor being shown in section. Fig. 3 is a detail face view of the governor. Fig. 4 is a section taken on line 4-4 of Fig. 3. Fig. 5 is a view partly in section, and partly in elevation, of one of the liquid fuel pumps operated by the governor and its connections.

45 The improved governor mechanism for regulating the amount of liquid-fuel supplied to the cylinders is illustrated as applied to a two-cylinder engine, comprising a base *a*, a crank-case *b* for each cylinder mounted upon the base, and cylinders *c* mounted upon the crank-cases respectively. A main-shaft *d* is suitably journaled in the 55 crank-case and has fly-wheels *e* secured

thereto, as well understood in the art, so that the fly-wheel will be driven by the operation of pistons in the cylinder *e*. A suitable ignition head *f* is secured to the upper end of each cylinder and an inspirator *g* of 60 suitable construction is connected to the ignition-head, to deliver liquid-fuel, such as hydrocarbon oil, into the cylinders. This liquid-fuel is forced to the inspirators, through pipes *h*, *h'* respectively connected 65 to pumps *k¹⁰*, *k¹¹* to which liquid-fuel is conducted by supply-pipe *k²¹* and branches *k³¹*. In the operation of these internal-combustion engines, the quantity of liquid-fuel supplied to the cylinders should vary according 70 to the speed of the engine, which is determined by the load imposed upon it and for that purpose the pumps *k¹⁰*, *k¹¹* are controlled by governor-mechanism, as herein-after set forth, whereby the pump-stroke is 75 varied according to the quantity of liquid-fuel to be forced to the inspirators.

80 Each pump comprises a cylinder 10 which is secured by a nut 12, to a supporting-bracket 11 which is secured to the engine-base *a*. A piston 13 slides in each cylinder 10 and a packing-box 14 is provided to prevent leakage of oil between the piston and the cylinder. Each piston is operated in one direction, by a spring 23 which engages a collar 24 on the piston, and the normal position into which the piston is operated by the spring is determined by an adjustable-stop which comprises a screw-threaded plug 19 having a stem 18 extending into a 85 recess 17 in the piston-end, to guide the outer end of the piston. Said plug 19 is held in assigned position by a clamp 20 which is connected by bolts 25 to the bracket 11. The stop comprises a head 21, whereby it may be turned and a washer 22 of slightly yielding material, such as rubber or leather, to cushion the piston. Check-valves 15 and 16 control the ingress and egress of the oil 90 to and from the pump cylinder, respectively, so that when the piston is operated in the cylinder, liquid will be forced through the pipes *h*, *h'* by the pumps respectively, and by variation of the pump-stroke, the quantity of oil forced to the ignition-chambers of the engine-cylinders, will be varied. The 95 adjustable stops for the pistons provide convenient means for adjusting the normal position of the piston for the purpose of compensating for any wear in the operation of 100 105 110

the governor-mechanism by which the pistons are operated.

The governor-mechanism comprises a lever k , which is pivoted to one of the fly-wheels e by a bolt k' , the latter serving as a fulcrum which has a fixed relation to, and is disposed eccentrically with respect to, the axis of the engine-shaft and the fly-wheel. The lever is weighted at one end, as at k^2 , 5 and is provided, adjacent one of its ends, with adjustable stop-screws 27 and 28 at opposite sides thereof, which are adapted to engage abutments 29 and 30 on the fly-wheel respectively to limit the movement 10 of the lever about its fulcrum.

A spring 31 is connected to the lever, as at 32, and is adjustably connected to the fly-wheel, as at 33, to hold the lever normally in one of its alternative positions, determined 15 by engagement of stop-screw 27 with abutment 29 on the fly-wheel. This spring also permits the lever to swing about its pivot, when inertia causes the lever to lag with respect to the fly-wheel and to restore the lever, 20 as the speed of the fly-wheel decreases. A friction-device 34, consisting of a piece of leather or similar material, is mounted at one end of lever k and is adapted to rub against or engage a surface 35 on the fly-wheel to retard the movement of the lever 25 relatively to the fly-wheel. A circular flange l integrally formed on lever k is eccentrically disposed with respect to the lever fulcrum k' , and said flange forms an eccentric, the center of which swings in an arc from lever-fulcrum k' . The shaft d extends through said eccentric-flange and as the center of the eccentric recedes from and approaches the axis of said shaft its eccentricity relatively 30 to the shaft is correspondingly varied to 35 variably operate the mechanism for operating the fuel-pumps. It will be observed that this construction avoids the necessity of slidably engaging elements between the engine-shaft or the fly-wheel and the lever, for causing variation of the operation of the eccentric; and that the stop-screws and eccentric are disposed on the lever which 40 can be conveniently machined or formed 45 while no machine work is necessary on the fly-wheel, which is more difficult to handle.

The mechanism for operating the pump k^{10} comprises a lever m , which is pivotally sustained by a bolt m' secured in a bracket m^2 which is secured to one of the crank-cases b . Lever m has journaled thereon, a friction-roller m^3 and its lower end is forked and extended, as at m^4 , to engage collar 24 on the piston 13 of pump k^{10} . The other 50 pump k^{11} is operated by a similar lever m oppositely disposed with respect to the operating lever for pump k^{10} and has a friction-roller m^5 , which is engaged by the opposite side of the cam l . A spring m^6 is connected 55 to levers m and holds their friction-rollers

in engagement with the cam l . When the engine is operating at low speed, or insufficient speed to affect the governor, eccentric l will be disposed from maximum eccentricity and at such time a comparatively long 70 stroke will be imparted to the pump-pistons 13, to inject a large quantity of liquid-fuel into the engine cylinders. The lag on lever k will be greater when the engine is traveling at high speed causing it to overcome the 75 resistance of spring 31 and friction-device 34, to shift the lever and eccentric, so it will be less eccentric to the axis of the fly-wheel or crank-shaft and will correspondingly shorten the stroke of lever m , so that 80 the stroke of piston 13 will be relatively decreased. The lever-stroke is normally greater than the piston-stroke, so that there will be lost-motion between the levers and the pistons and this lost-motion connection 85 causes the levers to tap and quickly operate the pump-pistons to force oil through the pipes h , h' to the cylinders, in proportion to the load imposed upon the engine. By adjustment of stops 19, the normal position 90 of pistons 13 in cylinders 10 and the positions of collars 24 relatively to the stroke of the levers m , may be varied without adjustment of the governor-mechanism and this feature is of advantage, because adjustment to a nicety may be established without disturbing the governor-mechanism, and in this manner any slight wear in the governor 95 connections may be compensated. By adjusting stop-screws 27 and 29, the play of 100 lever k and the eccentric of cam m , may be varied.

In starting the engine, it is necessary to operate the pumps manually and for this purpose an arm n is pivotally connected to the pivot m' of one of the levers m and this arm is provided with an abutment n' for engaging an abutment on said lever which will operate the latter to operate the piston 13 to which it is applied. A bell-crank lever o is pivoted to the pivot m' of the other lever m , and lever o and arm n are provided with meshing teeth o' for causing said lever and arm n to be rocked together, to cause both of the levers m to be operated, lever o being also provided with an abutment o^2 for engaging its associated lever m and with a handle o^3 and a locking-lever o^4 , whereby the lever o and arm n may be locked in their normal 110 position, while the governor-mechanism is operative. Lever o^4 may be of any well known construction, being pivoted to lever o between its ends and provided with a stud or pin at its lower end which is adapted to pass through a hole in lever o and into holes in the bracket m^2 as indicated in Figs. 1 and 2. Provision is also made for locking lever o in position to hold lever m out of the path of eccentric l , to render the pumps in- 115 120 125 130

operative by the eccentric, and when thus locked the supply of fuel to the engine cylinders will cease and the engine will stop.

The invention is not to be understood as restricted to the details shown and described, since these may be modified within the scope of the appended claims, without departing from the spirit and scope of the invention.

Having thus described the invention, what I claim as new and desire to secure by Letters Patent, is:

1. In an internal combustion engine, the combination of a shaft, a fly-wheel on said shaft, a lever pivoted to the fly-wheel eccentric with respect to the axis of the shaft and in close proximity to the axis, the lever comprising oppositely extending arms, an eccentric on said lever, a spring having one of its ends connected to the fly-wheel and its other end to one of the arms of said lever, a fuel pump, and means operated by the eccentric for operating the pump.

2. In an internal combustion engine, the combination of a shaft, a fly-wheel on said shaft, a lever movably connected to said fly-wheel and rotated thereby, abutments on the fly-wheel, adjustable stops on the lever for engaging said abutments to limit the movement of the lever, an eccentric operated by said lever, a fuel-pump, and connections for operating the pump by the eccentric.

3. In an internal combustion engine, the combination of a shaft, a fly-wheel on said shaft, a lever pivotally and eccentrically connected to said fly-wheel and rotated thereby, an abutment on the fly-wheel, adjustable stops on the lever for engaging said abutment to limit the pivotal movement of the lever, a fuel pump, pump-operating means on the lever, and connections for operating the pump by the pump-operating means on the lever.

4. In an internal combustion engine, the combination of a shaft, a lever mounted to be rotated by the shaft and eccentrically pivoted with respect to the axis of the shaft, an eccentric on the lever, a fuel pump comprising a piston, and mechanism for operating the pump by the eccentric comprising a lever having a lost-motion connection with the piston and an adjustable stop for varying the stroke of the piston.

5. In an internal combustion engine, the

combination of a shaft, a lever mounted to be rotated by and eccentrically pivoted with respect to the shaft, an eccentric operated by said lever, a fuel-pump comprising a piston, and mechanism for operating the pump by the eccentric, comprising a lever having a lost-motion connection with the piston, a spring for operating the piston in one direction, and an adjustable stop for varying the stroke of the piston.

6. In an internal combustion engine, the combination of a shaft, a lever mounted to be rotated by and eccentrically pivoted with respect to the shaft, pump-operating means on the lever, a fuel pump and mechanism for operating the pump by means of the lever, comprising a piston having a lost-motion connection with said lever, a guide extending into the end of said piston, and a stop for limiting the movement of the piston in one direction provided with a screw for adjusting the stop.

7. In an internal combustion engine, the combination of a shaft, pumps for supplying fuel to the engine, a lever mounted to be rotated by the shaft and eccentrically pivoted with respect to the axis of the shaft, an eccentric on said lever, levers disposed at opposite sides of the eccentric respectively, for operating the pumps, said levers having a lost-motion connection with the pumps, each pump comprising a piston operated by one of the latter levers, a stop for limiting the movement of each piston in one direction, respectively, and means for adjusting the stops to vary the stroke of the pistons.

8. In an internal combustion engine, the combination of a shaft, a lever mounted to be rotated by the shaft, an eccentric operated by said lever, a fuel-pump, mechanism for operating the pump by the eccentric comprising a lever, the pump comprising a piston operated by the latter lever, a guide extending into the end of the piston, a stop for limiting the movement of the piston in one direction, a screw-threaded-means for adjusting the stop, and clamp for securing the stop in assigned position.
